ABSTRACT

An abrasive medium is described consisting of finely divided abrasive particles uniformly distributed in a semifolid, difficultly flowable rubberlike plastic material of the consistency of putty and which forms a substantially solid matrix in carrying out the method of this invention which comprises forcing the medium over an internal surface in abrading contact therewith. Representatives of such plastic material are silicone putty or silicone rubber and a nonvulcanized plastic rubberlike putty. Two forms of apparatus for carrying out the method are disclosed. The workpiece is held between two cylinders with an opening through the workpiece in communication with the adjacent cylinder chambers in which reciprocating pistons move the medium alternately from one cylinder through the workpiece opening into the other cylinder.

APPARATUS FOR ABRADING BY EXTRUSION AND ABRADING MEDIUM

This application is a continuation-in-part of my copending application, Ser. No. 720,913, filed Apr. 12, 1968, now U.S. Pat. No. 3,521,412, dated July 21, 1970 which was a continuation-in-part of my application, Ser. No. 506,472, filed Nov. 5, 1965 now abandoned.

This invention relates to improvements in apparatus for honing or abrading by extruding as well as for the honing medium itself. The invention relates to honing or abrading of an internal surface comprising steps of passing over the surface to be finished in abrasive contact therewith, a semisolid, difficultly flowable plastic material of the consistency of putty permeated with finely divided abrasive particles while holding the plastic material confined in pressure contact with the surface to be finished. The special value of this invention is believed to be in the removal of burrs, breaking corners, and improving the finish of the interior of surfaces of intricately shaped products.

The design of many products necessitates the machining of intersecting bores, flats, slots, keyways and splines, and the machining of these various shapes invariably produces a sharp corner of a raised burr at the conjunction of such surfaces. This invention is particularly useful where such intersecting surfaces occur in the internal part of a workpiece which cannot be finished by the usual methods of grinding, lapping or the usual known kinds of honing.

The end use of many products in the aeromotive, aircraft and aerospace industries is such that a small particle of metal may cause failure to the entire engine or other operating system. The flaking off of a projecting burr, therefore, is a risk that is always present in the assembly of these products. Again, the sharp corner resulting from the above-mentioned machining operations, may be a point of stress concentration and possible failure of a critical part. The blending of the sharp corners with a radius materially reduces this stress concentration.

In detail, the purpose of this process includes the following:

- a. to provide a means of removing burrs from the interior and exterior surfaces of various products;
- b. to improve the surface finish of surfaces produced by various machining operations better than, or which cannot be improved by, conventional methods;
- c. to provide a means of adding a radius or a blending of sharp corners of the products;
- d. to provide a means of finishing the inside diameter of straight-bored products to exceptionally fine finish;
- e. to improve surface finish quality in nonsymmetrical or otherwise inaccessible cavities, galleries or manifolds; and
- f. to provide a means of automatically or semiautomatically performing these operations, with a controlled cycle, eliminating the operator variable and its resultant high cost and low quality.

This invention is an improvement over commonly used methods and apparatus for finishing parts in use today. The most commonly used method is manual, utilizing files, rotary burr tools or stones. Such manual operations are not satisfactory in that the location of the surface requiring burr removal may be so inaccessible that satisfactory quality levels cannot be attained, or may require such a degree of physical dexterity that only a few can perform the operation properly. This results in poor quality and a high percentage of scrap. Furthermore, manual operations are difficult to control and are usually erratic in cost per piece. They also increase inspection costs because of the erratic performance.

Another known method is vapor blasting which incorporates an abrasive slurry which is forced against the product at relatively high velocity. The impingement of the abrasive particles on the surface of the product erodes or abrades away the surface. This process has almost no effect on surfaces located interiorly of the product.

Sandblasting involves the use of abrasive particles thrown at high speed by compressed air or a mechanical flinger. Here again, this application has no value for interior surfaces.

Shotblasting uses cast iron shot, steel shot, or glass beads at high velocities as in the case of sandblasting. This operation is more nearly a peening over of the burr rather than a clean removal.

- 5 Tumbling agitates the product in a mixture of abrasive particles, stones, or jacks. These processes are carried out at low pressure and low velocity. The more exposed surfaces receive the most action. Here again, interior surfaces receive little or no abrasive effect.
- 10 The present invention incorporates the use of a plastic or semisolid medium at room temperature containing abrasive particles distributed substantially uniformly throughout. The purpose of the semisolid medium is to transport the abrasive particles through the product being deburred in order to permit the abrasive particles to remove the upraised metal and to round the corners as it passes, or to otherwise remove material from an internal surface.
- 15 Another purpose of the semisolid medium is to hold the abrasive particles in suspension so that they will be pressed firmly against the surface of the product when the medium passes through the openings as taught hereinafter, so that the abrasive effect is at a maximum, and uniformly distributed over the surface treated.
- 20 Another purpose of the semisolid medium is to provide a relatively firm backing for the abrasive, when the medium is under pressure, in order to increase the cutting action of the abrasive against the surface being treated, while still being plastic enough to flow through the product in order to reach all required surfaces.
- 25 Another purpose of the semisolid medium is to provide a relatively firm backing for the abrasive, when the medium is under pressure, in order to increase the cutting action of the abrasive against the surface being treated, while still being plastic enough to flow through the product in order to reach all required surfaces.
- 30 It should be noted that a liquid slurry carrying abrasive material and pumped through the same kind of workpiece as treated by this invention would not have the required abrasive action nor would it strike all surfaces uniformly. Such liquid slurry would require high velocity of flow to provide maximum impingement of the abrasive particles against the surface treated. Under such conditions some areas would receive no abrasion at all.
- 35 Some differences between the medium used for abrasive action in this invention and those employing abrasive carried by a liquid or air or gaseous medium should be noted. In the present invention the medium used is a semisolid, forced through the product under pressure and with relatively low velocity in such a manner as to provide a maximum abrasive action and uniformity of finish. Processes using liquid or air as a medium rely on high velocity and low pressure. The semisolid, difficultly flowable medium of this invention provides a firm matrix or support for the abrasive particle as it passes over the surface treated. Other processes using liquid or air as a medium or vehicle rely on high velocity and impingement of the abrasive particle against the workpiece. Sharp corners requiring blending usually occur at a conjunction of two surfaces. Flow through or past the product, therefore, changes direction at these points. A change of direction of flow of the present semisolid, difficultly flowable medium, tends to increase the abrasive action of the medium in the present process at such conjunction of surfaces. A liquid or air medium, on the other hand, carrying abrasive particles, will tend toward reduced abrasive action at these points of change of direction, and, under high velocity, the turbulent flow used with such liquid and air mediums tends to create areas of substantially no particle motion, at points of changing direction, resulting in no abrasive action at these points.

- FIG. 1 is a central sectional view through one embodiment of this invention, the same being taken generally along the centerline of the cylinders of FIG. 3;
- FIG. 2 is a fragmental view similar to the upper portion of FIG. 1 and showing another position of the parts;
- FIG. 3 is a front plan view of the machine taken from the right-hand side of FIG. 1;
- FIG. 4 is a top plan view of the same;

- FIG. 5 is an enlarged fragmental sectional view taken near one end of one of the hydraulic cylinders shown in FIGS. 1, 2 and 3;

FIG. 6 is a diagrammatic view showing an electrical control for the machine illustrated in FIGS. 1 through 5;

FIG. 7 is a diagrammatic view showing the control for the pressure fluid in the same machine;

FIG. 8 is a central sectional view through a second embodiment of this invention, the same being taken generally along the line 8—8 of FIG. 9; while

FIG. 9 is a fragmental top plan view of the machine of FIG. 8.

This invention will be described using a closed reciprocating system wherein the honing or abrading medium is passed back and forth through a workpiece to finish the same. It will be described using cylinder and piston motors but those familiar with the extruding of plastic materials will understand that the force might be otherwise applied to move semisolid plastic honing medium, such as a rotating screw or the like. Using a rotating screw, it is obvious that the housing medium might be passed in one direction only through the workpiece being treated and the honing medium might later be returned to the circulating or pressure device. This type of arrangement would be valuable in processing parts where certain advantages accrue by providing a single direction of flow. Such conditions might be, for instance, shoulders, faces or other areas which must not be affected by the honing process, or sharp corners of parts which must not be reduced.

Referring to FIGS. 1, 3 and 4 of the drawings, a base housing 10 is provided with an upstanding frame 11 for supporting the mechanism about to be described. The housing 10 may provide a hollow chamber for various control equipment but this feature has nothing to do with the present invention. Mounted on frame 11 are an upper plastic-extruding device 12 and a lower plastic-extruding device 13 and between them a workpiece holder 14. With one exception which will be later noted, the devices 12 and 13 are identical and one only will be described with reference numerals for the other being given a suffix "a." The device 12 comprises a double-acting cylinder 16 and piston motor 15 having a cylinder 16 in which is reciprocatable a piston 17 which operates a piston rod 18 which extends outwardly through a cylinder head 19 for a purpose to be described. The other end of the cylinder is closed with a cylinder head 20. The piston rod 18, below the cylinder head 19, is provided with a plunger 21 snugly fitting in a plastic material cylinder 22. The aligned cylinders 16 and 22 are carried in a generally C-shape bracket 23 having arms 24 and 25 which embrace the cylinder 22. The bracket 23 has an extension 26 which extends into an elongated slot 27 in the frame 11 so that bracket 23 may be adjusted vertically for handling different size workpieces. It is held in position by suitable bolts 28. A fine adjustment is provided by means of threaded screw 29 carrying a rotatable head 30 in a suitable pocket in the upper arm 24 of the bracket. This position is locked by means of a nut 31. In like manner, the aligned cylinders 16a and 22a are mounted in bracket 23a which is also vertically adjustable in frame 11 and held in position by the bolts 28a.

The chief difference between the upper pair of cylinders and the lower pair of cylinders resides in an arrangement whereby cylinder 22 is enabled to clamp a workpiece in the work holder 14. It is obvious that other means for holding the workpiece might be provided so that this difference is not essential to the operation of the invention. It will be noted that there is a collar 32 fixed to the cylinder 22 and spaced above the lower end of that cylinder. Between this collar and the upper arm 24 of the bracket is held a helical compression spring 33 and the cylinder 22 is slidably mounted at 34 in the arm 24. It is thus possible, as later described, to cause the plunger 21 to move upwardly as shown in FIG. 2 sufficiently to engage the upper head of cylinder 22 and lift this cylinder slightly above the upper arm 24 while compressing the spring 33 sufficiently to cause the lower cylinder head 35 to release a workpiece 36 resting on the work holder 14. A second collar 37 on cylinder 22 prevents excessive extension of spring 33 in case no workpiece is below the head 35.

It will be noted that there is no spring 33 associated with the lower cylinder and this cylinder is fixed in the supporting arm 24a. The cylinder is closed at its upper end with a cylinder head 35a which is here shown as integrally formed with the work holder 14 although it is obvious these two parts perform two functions and might be separate pieces properly secured to each other so as to position a workpiece 36 in proper position for this process.

The work holder in this form of device has a shoulder 38 against which the workpiece 36 is firmly positioned and in this embodiment of the invention a central opening or passage 39 in the workpiece 36 is aligned with a combined inlet and discharge opening 40 of cylinder 22 and a similar opening 40a of cylinder 22a. It will be noted that O-rings are provided above the workpiece at 41 and below the workpiece at 42 to prevent leakage at this point during operation of the process described herein.

Means is provided for supplying hydraulic fluid under pressure to and from each end of motor 15 by conduit 43 in cylinder head 20, conduit 44 in cylinder head 19, and conduits 43a and 44a in cylinder heads 20a and 19a, respectively.

In the control hereinafter described, it is desirable to have a switch actuated at the end of travel of piston 17 downwardly or piston 17a upwardly. A novel arrangement for actuating such a switch is shown in FIG. 5. This is described in connection with cylinder 16a but identical structure is shown at 52 at the upper end of cylinder 16. In the cylinder head 20a a button 45 is mounted for reciprocation parallel to the axis of the cylinder. To this end, a bore is provided in the cylinder head and the button is formed on the end of a plunger which is normally urged outwardly by a spring 46 compressed between the lower end of the plunger and a recess in the cylinder head closed by screw 47. A cross bore 48 in the plunger carries a switch actuator pin 49 which extends outwardly beyond the cylinder head through an elongated slot 50 which permits travel of the pin to the dot-dash position as viewed in FIG. 5 when button 45 is depressed by an approaching piston such as 17a. The plunger carrying button 45 is sealed in its bore against leakage of hydraulic fluid by O-ring sealing means 51. In actual operation, normally open switch 52, connected with cylinder 16, and normally closed switch 52a, connected with cylinder 16a, are provided to be reversed by pin 49 when the associated piston reaches the end of its travel.

A second embodiment of this invention is shown in FIGS. 8 and 9. In general, this second embodiment is like the first embodiment except for the means urging the upper plastic material cylinder downwardly against the workpiece and its control means for lifting the same cylinder upwardly at the end of an operation to release the workpiece.

Referring to FIGS. 8 and 9, the frame of the machine consists of a table portion 80 and an upstanding pillar portion 81. Two similar devices push the plastic material through the workpiece. These are substantially identical and each consists of a cylinder and piston motor 82 or 82a longitudinally aligned with an associated plastic material handling cylinder 83 or 83a. The piston rod 82' of the motor 82 carries at its outer end a plunger 84 which is tightly sealed to the inner wall of cylinder 83. In like manner, the piston rod 82a' of motor 82a carries plunger 84a for reciprocation in cylinder 83a. The device 82a, 83a is fixed relative to the table 80 while the device 82, 83 is mounted in a bracket 85 for slight vertical movement as will presently appear.

The workpiece 86 is positioned on cap 87a, normally against a shoulder 88, with the through opening 86a of the workpiece aligned with an opening 89 in the cap 87a, of cylinder 83a, and another opening 90 in the cap 87 fixed to the end of cylinder 83. It will be understood that the passageway 86a in the workpiece is normally not a straight through passageway and this is only diagrammatic to indicate any passageway through which the plastic material is to be pushed.

The bracket 85 is generally U-shape in horizontal section having a backplate 85a and top and bottom plates 85b. Means

is provided for raising and lowering the upper device 82, 83 to permit the insertion or removal of a workpiece 86 after which the upper device is moved down against the workpiece to hold it firmly during the abrading operation of this invention. This means comprises a cylinder and piston motor 91 which cylinder is supported by the table 80 and whose piston 91a is reciprocatable by a pressure fluid supplied at one of the inlet-outlet conduits 92 and relieved at the other conduit 92 depending upon which direction the piston 91a is to be driven. The piston 91b of this motor 91 has an adjustable connection with a projection 93 which is rigidly fixed to the plate 85a of the bracket 85. The connection between piston rod 91b and the projection 93 is adjusted vertically at the factory to accommodate a range of thicknesses of workpiece 86. The bracket 85 is supported for vertical movement relative to the pillar 81 by means of L-shaped ways 94, best seen in FIG. 9, which embrace a plate 95 secured to the wall 81a of the pillar 81. Motors 82 and 82a are double acting and are supplied with pressure fluid from means not shown at the connection A and B of cylinder 82 and connections C and D of cylinder 82a.

The operation of this second embodiment should now be clear. The supply and control of pressure fluid and electrical controls for the upper and lower devices of FIG. 8 is like that shown in connection with FIGS. 1 through 5. For clarity, the control devices 52 and 52a actuated by pin 49 in the first embodiment are not shown but are used for automatic operation for this second embodiment. Piston 91a is first moved upwardly sufficiently to allow the workpiece 86 to be engaged against the fixed shoulder 88 which aligns the passageways for flow of the plastic material in passages 89, 86a and 90. In the position of the parts in FIG. 8, the cylinder 83a is filled with the plastic abrasive material as will be readily understood. Piston 91a is then moved downwardly to firmly clamp the workpiece 86 between the cap 87 of the upper device and cap 87a of the lower device. The upper and lower motors 82 and 82a are then operated alternately to first push the plastic material upwardly by means of plunger 84a and downwardly by means of plunger 84 until the abrading action on the workpiece 86 is performed. Piston 91a is then moved upwardly sufficiently to release the workpiece 86 and another piece is placed in position.

The medium for use in this invention is a semisolid, difficultly flowable rubberlike plastic material having the consistency of putty at room temperature and uniformly permeated with finely divided abrasive particles. It is necessary to the operation of this invention that the plastic carrier have sufficient body at high pressure and low velocity to press the abrasive particles against the surface to be treated with sufficient force to produce the result desired. One suitable material for carrying the abrasive particles is silicone putty, sometimes called silicone rubber, in the grade indicated by General Electric Company as SS-91. This material has a bounce or rebound of 25 to 50 percent when a 12-gram ball of the putty at 70° to 78° F. is dropped from a height of 100 inches onto a smooth-surfaced soapstone block. The material has a resilience of 10 percent 20 percent when measured with a Bashore Resiliometer of the Precision Scientific Company of Chicago, at room temperature and with a special ½-ounce drop weight. The same putty has a penetration of 1.5 to 10 mm. in 5 seconds using a Precision Universal Penetrometer with a ¼-inch-diameter foot on a 47.5-gram test rod with no external loading. This test is made at least 24 hours after the batch of putty is dropped or first formed in order to get a reliable test.

By definition, silicone putty, or silicone rubber, is a solid. However, it exhibits many of the characteristics of a fluid. It is compressible, and therefore expandable. Under pressure it becomes less flowable and more like a solid. It conforms exactly to the shape of whatever confines it and this insures 100 percent abrasion on all parts or corners that the putty mixture is compressed against or forced through.

For most uses, a small amount of plasticizer or softener is used with the above-mentioned putty to render it slightly more

plastic and flowable than in its original form. One mixture successfully used comprises:

Example I

5	G.E. silicone putty, SS-91 grade	35%
	Isopropyl Stearate (softener)	3%
	Silicone grease (adds lubricity)	2%
	Silicone carbide abrasive No. 120 grade	60%

10 In jobs requiring somewhat greater flowability, the isopropyl stearate or other suitable softener would be slightly increased.

Example II

15	Silicone putty	1 lb.
	Aluminum oxide (100 grain size)	6 lb.
	Methyl phenyl silicone fluid, 125 Centistoke, produced by the General Electric Co.	1 oz.
20	Tetrafluoroethylene powder	2 oz.

Another difficultly flowable plastic material which is a suitable medium for carrying the finely divided abrasive material of this invention is a nonvulcanized plastic rubber putty sold by

25 the Eberhard-Faber Company under the trade name Kneaded Rubber. As used herein "plastic rubber putty" is intended to include synthetic plastics having similar rubberlike characteristics. Both this material, and the silicone putty, may be used for tough jobs where the putty material has substantially

30 the consistency of glazing putty after it has stood in a can for some time so that most of the oil has separated out to the top of the material. However, for easier jobs or those jobs where the passageways to be traversed by the medium of this invention are small in cross section, the basic putty material of this

35 invention works better if it is plasticized or softened somewhat by working into it a small amount of methyl phenyl silicone fluid, 125 Centistoke, produced by the General Electric Company, oleic acid, isopropyl palmitate, or isopropyl stearate. Other softeners might be substituted for those mentioned 40 herein. In any case, the basic plastic putty material is seldom reduced to a point where it is softer than a glazier's putty as he applies it around the edge of a window pane.

Another additive to the basic plastic putty material will be 45 referred to herein as a "hardener." Small additions of this ingredient will result in a stiffening or toughening of the vehicle medium. This hardener will cause the plastic putty material to retain a certain compactness to better press the abrasive against the burr to be removed. This hardener will also act as 50 an internal lubricant, that is, within the medium when there is evidence of plugging or blockage. Suitable hardeners are tetrafluoroethylene, commonly known as Teflon, in the form of small beads or powder and levigated talc.

The additives, such as the reducers and hardeners mentioned above, are usually used in combination. Should it be desired to increase the flowability of the abrading and honing medium, then the reducer should be added. Should it be deemed desirable to toughen the batch, an ounce of hardener may require 3 or 4 ounces of reducer to complete the conditioning. Again, if a batch is softened by using the reducer, a 60 quarter ounce of the hardener will show a response in retaining compactness. The amounts refer to one pound of the putty material as a base.

Example III

65	Kneaded Rubber	1 lb.
	Aluminum oxide (100 grain size)	4 lb.
	Silicone fluid	3 oz.
	Teflon powder	1 oz.

70 Obviously, the abrasive used in the carrier putty will be varied to suit the job. A satisfactory abrasive to use in working on steel is boron carbide (B C) which is readily obtainable from Norton Company in standard grit size. An abrasive for

many applications is aluminum oxide. Other abrasives might include diamond dust, silicon carbide, rouge, corundum, garnet, alundum, glass, or in some unusual operations softer material such as fiber or shell material. Commonly, the abrasive per pound of putty material will weigh from about 2 pounds to about 15 pounds.

In operation of the apparatus described, with a workpiece clamped between the two cylinder pairs as shown in FIG. 1, and with piston 17 and plunger 21 in uppermost position and piston 17a and 21a in lowermost position, the cylinder 22a is filled with the silicone putty carrier permeated with a suitable abrasive as above described. In one form of the invention, cylinders 22 and 22a are slightly less than 3 inches in diameter and about 10 inches long and one of them will hold about 3 pounds of the putty and abrasive mixture. Motor 15a is then actuated to drive piston 17a and plunger 21a upwardly thus forcing the honing material through the passageway 39 in the workpiece 36 and up into the cylinder 22. When piston 17a reaches the upper end of its travel, it hits a button 45 as described in connection with FIG. 5 and causes actuation of switch 52a. This reverses the flow of hydraulic fluid through conduits 43a and 44a in a direction to drive piston 17a downwardly. At the same time it supplies hydraulic fluid to motor 15 so as to drive piston 17 and plunger 21 downwardly. This causes reverse flow of the honing material through the passageway 39 of the workpiece and again redeposits the honing material in the lower cylinder 22a. When piston 17 reaches the lower limit of its travel, it hits its associated button 45 and actuates switch 52 to start a timer and to reverse the hydraulic flow so as to enter at 44 and exit at 43 driving piston 17 upwardly until the timer stops this action. Preferably, this action is set to move cylinder 22 to the position shown in FIG. 2 so as to compress spring 33 and release the workpiece 36 from the clamping action so that it may be removed and a new workpiece put in its place. The timer preferably is arranged to hold cylinder 22 in the position of FIG. 2 for a few seconds to enable the positioning of a new workpiece in work holder 14. Then, when the timer times out, the pressure under piston 17 is released and spring 33 causes cylinder head 35 to clamp the new workpiece. FIG. 6 shows a diagram of a control for carrying out the above cycle.

The diagram of FIG. 6 indicates a power source 55, a transformer 56, an emergency stop button 57, a pump start button 58a for motor pump 58, a circuit-holding relay M1, and over-load relays 59. Closing button 58a starts the motorized pump 58 to supply hydraulic fluid under pressure in the fluid control system shown in FIG. 7. In starting the operation of the machine, after the workpiece is suitably positioned as shown in FIGS. 1 and 2, start button 60 is closed which through normally closed control relay CR2 and lines 61 and 62 energizes control relay CR1 which closes contacts 63 to provide a holding circuit. Through line 64 hydraulic solenoid HS4 is energized which moves valve 65a toward the right causing pressure fluid to be supplied through the line 44a beneath piston 17a driving this piston upwardly while the hydraulic fluid is discharged through lines 43a and 66 back to the pump reservoir. This drives the flowable plastic honing material upwardly from cylinder 22a through the workpiece and into cylinder 22, the piston 17 of which is at this time in the uppermost position as will later appear. When piston 17a reaches the end of its travel, it strikes button 45 so as to cause rod 49 to reverse the position of the normally closed limit switch 1 or 52a. This deenergizes solenoid HS4 and control relay CR1. In its reversed position, limit switch LS1 engages contact 67 and, through line 68, energizes control relay 2 shown on the diagram as control relay CR2. At the same time, through line 69, solenoids HS2 and HS3 are energized so as to deliver hydraulic pressure fluid through line 43 to the upper portion of the cylinder 16 driving piston 17 downwardly while discharging hydraulic fluid through line 44 back to the reservoir. Solenoid HS3 causes pressure fluid to be delivered through line 66 and line 43 to the upper end of cylinder 16a driving piston 17a downwardly while pressure fluid is discharged through line

44a to reservoir. When piston 17 in the upper cylinder reaches the lower end of its travel, through button 45, limit switch LS2 or switch 52 which is normally open is reversed and moved to closed position which energizes the time delay relay TD. This opens the normally closed contact 70 thus deenergizing solenoids HS2 and HS3. It also closes contacts 71 in line 72 which energizes solenoid HS1 through line 73 and a pilot light A in line 74. Energization of the time delay relay TD closes the normally open contacts at 75 so as to energize control relay CR2 through line 76 and this closes the normally open contacts 77 as long as the time delay switch 78 remains closed by the timing element. The energization of solenoid HS1 delivers pressure fluid through line 44 to the lower end of cylinder 16 driving piston 17 upward while pressure fluid discharges through line 43. The time delay is so adjusted that cylinder 22 is raised to the position indicated in FIG. 2 so that the lower cylinder head releases the workpiece 36 so that it may be removed and changed. So long as the light A remains lit, the operator knows that he has time to reinsert another workpiece. Upon the opening of the time delay switch 78, solenoid HS1 is deenergized and cylinder 22 will move downwardly toward clamping position. If a new workpiece has not been inserted in the work holder 14 at this time, it is only necessary to close the jog switch 79 which will energize solenoid HS1 causing the cylinder 22 to move upwardly so that one may insert a fresh workpiece. The parts are now in position for a new cycle.

It is obvious that the above cycle could be controlled manually or it might well be made automatic by merely having the machine operate the start button automatically when the new workpiece is clamped in position.

A machine operating as above described and utilizing the typical batch of honing medium hereinabove defined using the silicone putty with the isopropyl stearate softener developed 35 1,500 pounds per square inch in the hydraulic pump and expelled the honing medium from the cylinders at the rate of about three-quarters of an inch per second. The passageway 39 through the workpiece in this example caused a restriction of the flow so that the flow was accelerated to about 30 inches per second. In this case, one pass of the honing medium upwardly and then downwardly removed the typical grinding burrs and produced a uniform radius condition on all affected edges of 0.002 inches to 0.005 inches. The surface finish on the treated surfaces was of the order of 4 to 8 R.M.S. and this 40 is the more predictable if the abrasive grit is of substantially uniform size in a given honing medium for a given purpose. Pressure on the honing medium is seldom less than 500 p.s.i.

It is necessary to hold the workpiece between the upper and 50 lower pairs of cylinders so as to confine the flow of the honing medium past the area to be treated. In the case of an opening through the workpiece, special adapters may be called for to pass the honing medium into a certain opening and out of a certain opening in the workpiece. This is merely the skill of the industry.

This invention may be utilized to hone or abrade machined parts, die castings, forgings, sand castings, investment castings and extruded shapes. It is applicable to all materials such as steel, aluminum, brass, bronze, plastics, glass and other compositions and materials as needed.

It should be noted that the silicone putty is particularly useful in this purpose as it is well known that this material becomes harder when subjected to additional pressure such as when turning a corner or being forced through a restricted passageway as in the honing processes herein described. The abrasive putty used in this invention may be defined as "rheoplectic" in that its apparent viscosity increases with time under a suddenly applied stress.

In general, the tougher jobs take the thickest plastic putty 70 material and the largest abrasive size. The easier jobs take the thinner putty material and a smaller abrasive size down to as small as 6 to 10 microns.

The major ingredient in the honing medium of this invention is the abrasive grain employed. The amount will usually vary from about 2 to 4 pounds of abrasive particles in the

smaller sizes per pound of the putty material, up to as much as 12 or 15 pounds of abrasive particles in the larger grain sizes per pound of the plastic putty material.

The honing medium of this invention, which acts as a surface abrading tool, is unique for the reason that the abrasive grain is held or contained in a random repositioning arrangement in a plastic matrix. The usual concept is that of an abrasive "stone" or lap wherein the grain particle is fixed and presents one cutting point or edge which is maintained until dulling causes removal by means of a dressing operation. The total grain particles in use in the process of this invention are sharp until the sum of all points or edges have been exposed many times. The internal shearing which occurs when in use results in a continuous resharpening which extends the life of the medium to many hundreds of hours.

The finishing method of this invention may be described as "soft" in that there is no instant of great energy expended. The finished pattern, while directional, is not consistent. The finish mark caused by any grain particle cannot be traced beyond the instant of contact and the opportunities for random repositioning and recontact are all but limitless.

The fastest cutting action, which is also consistent with the most uniform results, occurs when the medium exhibits an oily nonadhering contact with the workpiece. It would appear that when in this condition the medium has the greatest opportunity to pass through the part at a constant cross-sectional pace. This is contrary to a fluid flow which is greatest through the center and supposedly "zero" along the wall.

What is claimed is:

1. Apparatus for honing by extruding a flowable plastic abrading material through a through passage including a workpiece wall to be abraded and comprising a frame, two plastic-extruding positive displacement expandable chamber devices on said frame on opposite sides of a workpiece holder, each of said devices having a combined inlet and discharge opening for flow of said plastic material toward and away from said holder, means for holding a workpiece with said passage in flow alignment with said openings, and means for causing one of said devices to force said plastic material through said passage and openings into the other of said devices and for causing the other of said devices to force said plastic material to flow in the opposite direction through said passage and openings into said one device, said frame rigidly holding said extruding devices and said workpiece holder.

2. Apparatus as defined in claim 1 wherein each of said devices comprises a double-acting cylinder and piston motor, a plastic material cylinder horizontally aligned with its associated motor cylinder, each said motor cylinder having a piston rod extending outwardly toward said workpiece holder

and a plunger on said rod snugly fitting into its associated plastic material cylinder, the plastic material cylinder of said other device having a mounting permitting cylinder movement longitudinally away from said workpiece, said workpiece-holding means comprising means urging said other plastic material cylinder toward and against said workpiece to clamp it between said devices, and control means for said other device for causing it to lift said cylinder after said flow of said plastic material in said opposite direction against said urging means sufficiently to release said workpiece.

3. Apparatus as defined in claim 2, wherein said means urging said other plastic material cylinder against said workpiece is a spring held by said frame, and said control means for said other device includes means for causing its plunger to traverse its coating cylinder away from said workpiece against the urging of said spring sufficiently to release said workpiece.

4. Apparatus as defined in claim 2, wherein said means urging said other plastic material cylinder against said workpiece is a pressure-fluid-actuated motor having means for urging said other plastic material cylinder toward and against said workpiece, and said control means for said other device includes means for causing said pressure-fluid-actuated motor to move said other plastic material cylinder away from said workpiece sufficiently to release said workpiece.

5. Apparatus as defined in claim 1 wherein said means causing said devices to force said plastic material first in one direction and then in the opposite direction includes a double-acting cylinder and piston motor for each device and control means for causing each of said motors in turn to cause flow of said plastic material through said workpiece.

6. Apparatus as defined in claim 5, wherein said control means comprises an actuator inside the cylinder of one of said motors engageable and movable to an actuated position by said associated piston near the end of its travel in a direction causing flow of said plastic material through said workpiece, and means operatively associated with said actuator in its actuated position for causing at least one of said devices to reverse the motion of its motor.

7. Apparatus as defined in claim 6 wherein said actuator comprises a button reciprocatably mounted in the cylinder head of said one motor and normally extending into said cylinder in position to be engaged and moved longitudinally of said cylinder by the approaching piston, spring means urging said button into said cylinder, means sealing said button in said cylinder head against leakage of pressure fluid out of said cylinder and a member carried by said button and exteriorly out through said head and adapted to operate a control member.

[57] ABSTRACT

An abrasive medium is described consisting of finely divided abrasive particles uniformly distributed in a semisolid difficultly flowable rubberlike plastic material of the consistency of putty and which forms a substantially solid matrix in carrying out the method of this invention which comprises forcing the medium over an internal surface in abrading contact therewith. Representatives of such plastic material are silicone putty or silicone rubber and a nonvulcanized plastic rubberlike putty. Two forms of apparatus for carrying out the method are disclosed. The workpiece is held between two cylinders with an opening through the workpiece in communication with the adjacent cylinder chambers in which reciprocating pistons move the medium alternately from one cylinder through the workpiece opening into the other cylinder.

**REEXAMINATION CERTIFICATE
ISSUED UNDER 35 U.S.C. 307.**

THE PATENT IS HEREBY AMENDED AS
INDICATED BELOW.

Matter enclosed in heavy brackets appeared in the patent, but has been deleted and is no longer a part of the patent; matter printed in italics indicates additions made to the patent.

AS A RESULT OF REEXAMINATION, IT HAS
BEEN DETERMINED THAT:

The patentability of claims 1, and 5-7 is confirmed.

Claim 4, having been finally determined to be unpatentable, is cancelled.

Claim 2 is determined to be patentable as amended:

2. Apparatus as defined in claim 1 wherein each of said devices comprises a double-acting cylinder and piston motor, a plastic material cylinder [horizontally] *vertically* aligned with its associated motor cylinder, each said motor cylinder having a piston rod extending outwardly toward said workpiece holder and a plunger on said rod snugly fitting into its associated plastic material cylinder, the plastic material cylinder of said other device having a mounting permitting cylinder movement longitudinally away from said workpiece, said workpieceholding means comprising means urging said other plastic material cylinder toward and against said workpiece to clamp it between said devices, and control means for said other device for causing it to lift said cylinder after said flow of said plastic material in said opposite direction against said urging means sufficiently to release said workpiece.

Claim 3, dependent on an amended claim, is determined to be patentable.
